UNITED STATES PATENT OFFICE.

ANTONIO SANSONE, OF KEOKUK, IOWA, ASSIGNOR OF ONE-HALF TO JOHN CHARLES AND FRANK SANSONE, OF KEOKUK, IOWA.

BANANA-CRATE.

SPECIFICATION forming part of Letters Patent No. 741,551, dated October 13, 1903.

Application filed January 15, 1903. Serial No. 139,217. (No model.)

To all whom it may concern:

Be it known that I, ANTONIO SANSONE, a citizen of the United States, residing at Keokuk, in the county of Lee and State of Iowa, have invented certain new and useful Improvements in Banana-Crates; and I do declare the following to be a full, clear, and exact description of the invention, such as will enable others skilled in the art to which it appertains to make and use the same.

My invention is an improved banana packing and shipping case; and it consists in the construction and arrangement of devices hereinafter fully described, and pointed out in the appended claims.

The object of my invention is to provide a light, cheap, and simple packing and shipping case which is adapted to be packed in a very small compass when empty and while being shipped to the user and which is adapted to be readily placed in condition to contain a bunch of bananas for shipment and is entirely sufficient in protecting the bananas during transportation.

In the accompanying drawings, Figure 1 is a perspective view, partly in section, of a banana packing and shipping case embodying my improvements, showing the same in its folded condition when disposed for the reception of a bunch of bananas. Fig. 2 is a perspective view of the same, showing the case in its original condition before being folded.

In the embodiment of my invention I construct the body of the packing and shipping case of a single sheet of strawboard, cardboard, or other suitable flexible material 1, adapted to be folded in a tubular cylindrical form, so that one of its side edges shall overlap the other. In the embodiment of my invention here shown I provide the side edges 2 of the body portion of the case with openings 3 for the reception of fastening devices 4, the latter being shown as paper-fasteners of the well-known form. The fastening devices are employed for fastening the edges of the body together after the same has been rolled or folded into tubular, cylindrical, or other suitable form. The body portion is here shown as provided on its outer side at its top and bottom edges with reinforcing-

strips 5, secured by the fastening devices 4, as indicated in the drawings, said fastening devices passing through said bands when the side edges of the body portion are overlapped and fastened together thereby. Any suitable number of these reinforcing-strips may be employed. On the inner side of the body portion at a suitable distance from the bottom thereof is secured the upper edge of the bottom head 6, which may be composed of burlap, sacking, or other suitable flexible fabric. The upper edge of the lower or bottom head 6 is here shown as secured to the body portion of the case by stitching; but it may be otherwise secured within the scope of my invention, and I do not limit myself in this particular. The case is further provided with a similar upper head 7, of burlap or other suitable flexible fabric.

It will be understood that a number of my improved packing-cases, when the same are extended as shown in Fig. 2, may be disposed and packed one on top of another for storage or shipment, so as to occupy but little room, and hence my improved packing and shipping cases may be packed and shipped when empty at very slight expense. Before using one of the cases the same will be folded or rolled into tubular, cylindrical, or other suitable form, as shown in Fig. 1, its overlapping edges secured together by the fasteners 4, and the lower flexible head will be gathered and tied by a string, as shown in Fig. 1, to adapt the lower head to support the weight of the bunch of bananas placed in the case. The upper edge of the lower head is secured in the body portion 1 at such a distance from the lower edge of the latter that when the lower head is thus gathered and tied it will prevent the bottom of the bunch of bananas from coming in contact with the floor on which the case stands. The upper side of the case after the bunch of bananas has been placed therein will be also gathered and tied, as shown.

From the foregoing description, taken in connection with the accompanying drawings, it is thought that the construction, operation, and advantages of my improved banana-crate will be readily apparent without requiring a more extended explanation.

Various changes in the form, proportion, and the minor details of construction may be resorted to without departing from the principle or sacrificing any of the advantages of 5 this invention.

Having thus described my invention, what I claim, and desire to secure by Letters Patent, is—

1. A case of the class described, comprising a relatively stiff body portion adapted to be rolled into tubular form, having means to detachably secure its opposite side edges together in overlapping relation and provided with reinforcing-bands on its outer side secured thereto by the said securing means, and heads of flexible fabric secured to the upper and lower portions of said relatively stiff body portion, substantially as described.

2. A blank for a fruit-crate comprising a relatively stiff rectangular body portion adapted to be rolled in tubular form and having means to detachably secure its opposite sides together when said sides are overlapped, the rectangular strip of fabric projecting outwardly from, and having its inner side secured to the said body near the upper end thereof and a similar strip of fabric lying wholly within the said body and having its inner side secured thereto, said strip being otherwise disconnected from said body, said fabric strips being both on the same side of the said body, and reinforcing-bands on the opposite side of the body and at points where the fabric strips are secured thereto, said reinforcing-bands being secured to the said body by the said securing means.

3. A blank for a fruit-crate comprising a relatively stiff rectangular body portion adapted to be rolled in tubular form and having means to detachably secure its opposite sides together when said sides are overlapped, the rectangular strip of fabric projecting outwardly from, and having its inner side secured to the said body near the upper end thereof and a similar strip of fabric lying wholly within the said body and having its inner side secured thereto, said strip being otherwise disconnected from said body, said fabric strips being both on the same side of the said body, substantially as described.

35 4. A blank for a fruit-crate comprising a relatively stiff rectangular body portion

wardly from, and having its inner side secured to the said body near the upper end thereof, and a similar strip of fabric lying wholly within the said body and having its inner side secured thereto, said strip being otherwise disconnected from said body, said fabric strips being both on the same side of the body, and reinforcing-bands on the opposite side of the body and at points where the fabric strips are secured thereto, said reinforcing-bands being secured to the said body by the said securing means.

5. A blank for a fruit-crate comprising a relatively stiff rectangular body portion adapted to be rolled in tubular form, a rectangular flexible fabric strip 7 projecting from the upper end of said body portion and having its lower edge secured thereto on its inner side, a bottom fabric strip 6 of flexible material on the inner side of the said body portion, wholly within the boundaries thereof and having its upper edge secured thereto, reinforcing-bands on the outer side of the body portion, extending from side to side thereof, and fastening devices adapted to secure the sides of the said body portion together when the same are overlapped and the body portion is rolled in tubular form, said fastening devices also securing the reinforcing-bands to the said body portion, substantially as described.

In testimony whereof I have hereunto set my hand in presence of two subscribing witnesses.

ANTONIO SANSONE.
